GARMENT HOLDER

Frank E. Jacobs, Altadena, Calif., assignor of one-half to R. C. Walker, Altadena, Calif.

Application November 26, 1935, Serial No. 51,583

2 Claims. (Cl. 24—243)

My invention relates more particularly to holders of the character referred to which are used at the end of an elastic strap or similar support for attachment to the top of hose or stockings for the purpose of holding them up in comfortable position.

Among the salient objects of my invention are: to provide a supporting device which can be very economically made and which will have means as a part thereof for frictionally holding the material of the hose or stocking as it is wrapped in the device, whereby to avoid pinching or otherwise injuring the material of which the garment is made; to provide a device which can be stamped out of sheet metal and formed into a strong, practical and relatively rigid device; to provide improved means for securing the loop or bail in place for attachment to the elastic or holding strap; to provide in a device of the kind referred to a hose engaging yoke pivotally connected at one end and at its other end having a finger or tongue with one free to receive a collar or short sleeve of friction material upon which the edge of the garment or hose is to be placed as it is turned with said yoke to wind a part of the garment or hose around said yoke; and in general, to provide a simple, economical and practical holder of the character referred to.

In order to more fully describe my invention, I have shown one practical embodiment thereof on the accompanying sheet of drawings, which I will now describe.

Figures 1, 2, and 3 are diagrammatic views showing three steps in applying the edge of a garment or stocking to the device to be supplied thereby;

Figure 4 is an edge view of the device, detached, and enlarged; and

Figure 5 is a front view of said device.

Referring now in detail to the drawing, my improved device includes a body 1, stamped out of sheet metal, and folded upon itself, with its upper end, of one side, rolled to form a sleeve 2, with the edge of the rolled portion resting inwardly against the upper end of the other side, as at 3, Fig. 4. A loop 4 has its ends inserted into said rolled portion, or sleeve 2, and constitutes an attaching loop or means for attachment to an elastic strap or similar support. Said body has two legs, as 5 and 6, and their lower ends are formed into sockets or bearings 5' and 6', in which are pivotally connected the arms 7 and 8, of a yoke 9, whereby said yoke can turn about its axis a complete circle between said legs 5 and 6, as will be clear from the drawing, and as indicated by the light broken line circle in Fig. 4.

An important part of my invention is the provision of a friction element on the yoke which will hold or cause to adhere thereto the edge of the garment or hose. In the present showing I have shown the yoke body having formed therein an upwardly projecting finger 10, with clearance space therearound, and being completely surrounded by the body of the yoke within which it is formed, and have placed over said finger a collar or short sleeve of tubular rubber 11, or similar material which projects through on both sides of the yoke body, as will be understood from Figs. 1, 2, and 3, and the light broken line showing in Fig. 4. This provides a friction element which is engaged on both sides by the garment as it is wound upon said yoke in the manner shown in Figs. 1, 2, and 3.

Referring to Figs. 1, 2, and 3, the garment or hose, or stocking is designated 12, and is shown in light broken lines. Fig. 1 indicates the first step where the edge of the garment 12 is laid over the top side of the yoke, the yoke is then, with the garment held thereon, turned through the main body, or the legs 5 and 6, and as in Fig. 3, continued on to the straight down position. Thus the garment edge is wound in the yoke as indicated by the light broken lines, and engages both sides of the rubber friction element 11, which prevents its slipping and becoming disengaged. Pull on the garment increases the contact with the element 11, and the garment is, therefore firmly held, and without any pinching or biting of the garment in a way which would injure the material. I am aware that the friction element 11 can be of any suitable material to create the necessary friction and that it can be held in place in different ways, and I do not limit the invention to the showing, except by the claims.

I claim:

1. In a garment holder, a part for holding the garment consisting of a yoke-like body having two arms, a finger surrounded by the body portion, and a collar of flexible friction material placed over said finger and being thicker than said body, whereby to project at both sides thereof to engage a garment wound thereon.

2. A garment holder stamped out of flat material with two supporting arms and a body portion, said arms being adapted to be pivotally supported, and said body having an opening therethrough for holding friction material therein, and friction material in said opening protruding at the opposite sides of said body to frictionally engage a garment wrapped around said body.
